DESIGN FOR A CHRISTMAS TREE ORNAMENT OR THE LIKE

Arpad Erdos, Astoria, Long Island, N. Y.

Application February 26, 1941, Serial No. 99,218

Term of patent 3½ years

To all whom it may concern:

Be it known that I, Arpad Erdos, a citizen of Hungary and resident of Astoria, Long Island, in the county of Queens and State of New York, have invented a new, original, and ornamental Design for a Christmas Tree Ornament or the like, of which the following is a specification, reference being had to the accompanying drawing, forming a part thereof.

Fig. 1 is a side elevational view of a Christmas tree ornament or the like showing my new design.

Fig. 2 is a front elevational view of the same looking in the direction of the line 2—2 of Fig. 1.

Fig. 3 is a top plan view of the same looking in the direction of the line 3—3 of Fig. 1.

I claim:

The ornamental design for a Christmas tree ornament or the like, substantially as shown.

ARPAD ERDOS.
